UNITED STATES PATENT OFFICE

2,463,143

ANAEROBE JAR

John H. Brewer, Baltimore, Md., assignor to Hynson, Westcott & Dunning, Incorporated, a corporation of Maryland

Application June 23, 1947, Serial No. 756,566

3 Claims. (Cl. 195—127)

1

An object of the present invention is to provide an anaerobe jar with improved means for chemically combining the oxygen content of the atmosphere within the jar which completely eliminates the danger of explosion.

It is customary to remove the oxygen from the atmosphere in an anaerobe jar by introducing hydrogen or other gas which is capable of chemical combination with oxygen into the jar and causing it to combine with the oxygen by means of an electrically heated catalyst. In spite of the fact that every effort has been made to avoid explosive reaction, explosions occasionally do occur and are quite dangerous because anaerobe jars generally are made of heavy glass and when they are exploded heavy pieces of glass are thrown with sufficient force to cause serious injury.

I have eliminated the danger of such explosions by eliminating the use of gaseous agents for combination with the oxygen. In accordance with my invention, carbon or a metal such as iron or other solid material which is capable of reacting with and binding oxygen but not explosively is used as the oxygen clean-up agent.

An anaerobe jar embodying my invention is illustrated in the accompanying drawings in which:

Fig. 1 is a central vertical section of the anaerobe jar and its accessories with some parts appearing in elevation.

Fig. 2 is a detail cross-section on the line 2—2 of Fig. 1.

Fig. 3 is a horizontal section, looking downward on the line 3—3 of Fig. 1.

Fig. 4 is a fractional central vertical section on the line 4—4 of Fig. 1.

Fig. 5 is a perspective view of the basket which supports the solid oxygen-fixing agent, and

Fig. 6 is a detail sectional view of the cover and basket in inverted position.

Referring to the drawings, 1 is the jar body and 2 the cover. The jar 1 should be transparent so that the contents may be observed and ordinarily is made of heavy glass like the standard museum jar and ordinarily is about 5 inches in diameter and about 8 inches deep. It will be understood, however, that my invention is not limited to the size or shape of the jar or the material of which it is made. It is within the scope of my invention for instance to use a jar formed of transparent synthetic resin or plastic or of non-transparent material.

The cover 2 may be made of any suitable material such as metal, e. g. it may be stamped out of heavy gauge stainless steel. As is customary,

2

the cover may be sealed to the jar by any suitable gasket material such as molding clay 3. The cover is held in place on the jar by means of the clamp 4 having fingers 5 which engage under the rim 6 of the jar and the screw 7 which is rotated to press against the cover by means of the knob or head 8.

The cover 2 preferably is dome-shaped, as illustrated, so as to contain or partly contain the oxygen getter basket and leave the space within the jar unobstructed to contain petri dishes and/or test tubes containing the anaerobic bacteria cultures under observation. The cover also preferably has a flat and unobstructed top surface so that it can be placed in inverted position as shown in Fig. 6 while the basket is being filled with the oxygen getter.

The cover has an opening in one side which is sealed by the plug 9 of electric insulating material containing the two electric conductors or electrodes 10, 10 adapted to receive electric current by way of the cord 11 and the detachable electric connector 12. The cover is provided also with a second opening into which is sealed the nipple 13 to which is connected the rubber tube 14 controlled by the pinch cock 15. This second opening and the nipple 13 are provided for use in the event that it is desired to evacuate the jar or to introduce a gas but it is not essential, constitutes no part of the present invention and may be omitted.

The cover further is provided with the inverted U-shaped bracket 16 which is shown as being spot welded at points 17, 17 to the cover. As will be apparent, any other construction which provides the two downwardly extending posts 19 and 20 may be substituted for the bracket 16. The posts 19 and 20 are provided with the pivot pins 21 and 22 upon which the basket 23 is pivotally supported. The basket 23 may be of any suitable shape such as the semi-cylindrical shape illustrated and consists essentially of the end walls 24 and 25 formed of an insulating and heat-resistant material such as slate, porcelain or the like and the wire screen 26. The end walls 24 and 25 are provided with the openings 27 and 28 to receive the pivot pins 21 and 22 and also carry the metal electrodes 29 and 30 which latter are connected by the flexible conductors 31 and 32 to the electrodes 10, 10. The ends of the electrodes 29 and 30 are positioned a suitable distance apart, say about five-sixteenth's of an inch, when the electric current supply is at about 110 volts and the oxygen getter has an electrical conductivity of the order of that of finely divided charcoal.

The screen wire portion 26 of the basket pre-

ferably is of a sufficiently fine mesh to prevent any substantial amount of the charcoal from sifting through. The basket may be provided with a cover, e. g. a screen wire cover 18 although this is not essential.

In operation the cover 2 is placed in the position shown in Fig. 6, the basket 23 is filled with finely divided charcoal or preferably with charcoal mixed with about 10% by volume of iron powder to render it more conductive, to a depth sufficient to cover the electrodes. The charcoal or charcoal-iron mixture preferably is lightly tamped into the basket around the electrodes, the basket cover put in place and the jar cover 2 is then turned right side up and placed on the jar. In turning the jar cover 2 from its inverted position to its upright position it should be turned on an axis parallel to the axis of the pivot pins 21 and 22 so as to permit the basket 23 to turn and maintain its upright position. After the cover 2 has been placed on the jar with the sealing member 3 in place, the jar of course containing the anaerobic bacterial cultures to be tested, the clamp 4 is applied and the electric connector 12 is attached. Current passes by way of the electrodes 10, 10, conductors 31 and 32 and electrodes 29 and 30 through the charcoal and heats it up sufficiently, preferably to a low red heat, to cause it to react with the oxygen in the atmosphere in the jar. Ordinarily from about 5 to about 20 minutes are required to consume all of the oxygen in the jar. The amount of carbon between the electrodes will, ordinarily be several times sufficient to consume the oxygen in the jar, that is, the jar can be used several times with a single filling of the basket with charcoal. The proximity of the electrodes readily may be adjusted, depending upon the conductivity of the carbon or carbon-iron or other powder used as oxygen getter, so as to produce the desired intensity of heating of the powder.

When the atmosphere in the jar is free of oxygen (this can be determined by oxygen indicators which, however, are not generally satisfactory or by testing the jar with known anaerobic bacteria or simply by continuing the passage of electric current for a sufficient length of time, say 20 minutes, to assure that all oxygen has been consumed) the connector 12 is removed. The heating of the oxygen getter by the passage of electric current and the heat of reaction between the oxygen getter and the oxygen tend to raise the temperature of the atmosphere within the jar but this rise in temperature generally does not exceed about 2° C. and is not objectionable.

It readily will be appreciated that the specific construction which has been described and illustrated is capable of extensive modification within the scope of my invention which I believe resides in the provision of means for contacting the atmosphere within an anaerobe jar with an electrically heated mass of solid material capable, when heated, of chemically combining with oxygen. Broadly the invention resides in the combination of a container for the finely divided oxygen getter and means for conveying electric current to the mass of oxygen getter to heat it to a temperature at which it reacts with the oxygen. More specifically, the invention resides in means for conveying electric current through the wall of the anaerobe jar and to a mass of the oxygen getter supported within the jar and in contact with the atmosphere therein. Still more specifically, the invention resides in a foraminous basket supported by the cover of the jar

and adapted to contain a mass of the oxygen getter and having electrodes in contact with said mass and electrical conductors extending from said electrodes and hermetically sealed through the cover of the jar and adapted to be connected to a source of electric current.

It is appreciated that the basket 23 which is mounted to rotate to inverted position to facilitate filling it with the oxygen getter and consequently is provided with flexible conductors for the electric current might be replaced by a great variety of forms of containers for the oxygen getter, for instance by a preformed capsule which might be inserted in a holder, e.g. between spring clips carried by the cover, and replaced by a new capsule from time to time or each time the jar is used for a new batch of cultures to be tested. In such a modification the electrical conductors would not have to be flexible and in fact the capsule supports, e.g. the spring clips, might be insulated from each other and serve also as the electric conductors to the capsule. The details of the illustrated embodiment of my invention were worked out to permit repeated filling of the basket with fresh charges of the oxygen getter from a package thereof but as stated this embodiment is merely illustrative of a variety of specific structures in which a renewable charge of solid oxygen getter is supported in contact with the atmosphere in the jar and heated to reaction temperature by electric current conducted by way of a permanent connection through the wall (or cover) of the jar.

I claim:

35. 1. An anaerobe jar comprising a jar body, a removable dome-shaped cover for said jar body, a bracket supported by said cover and having spaced apart posts extending downwardly therefrom, a foraminous basket rotatably supported between said posts, electrodes carried by and extending into the interior of the basket, an insulating plug extending through and sealing an opening in said cover, electric conductors sealed in and extending through said plug and flexible electric conductors 40 connecting said electrodes to said conductors sealed in said plug.

2. An anaerobe jar comprising a jar body and a removable cover, a foraminous container for a mass of solid material capable of reacting with oxygen supported by said cover within the jar, electrical conductors extending through said cover to said container and electrodes connected to said conductors and extending into the interior of said container.

55. 3. An anaerobe jar as defined in claim 2 in which the container is rotatably mounted and unbalanced to maintain its upright position.

JOHN H. BREWER.
